(57) **CLAIM**

The ornamental design for a footbed, as shown and described.

DESCRIPTION

FIG. 1 is a top perspective view of a footbed showing my new design;

FIG. 2 is a top plan view thereof;

FIG. 3 is a right side elevational view thereof;

FIG. 4 is a left side elevational view thereof;

FIG. 5 is a front elevational view thereof; and,

FIG. 6 is a rear elevational view thereof.

The broken lines showing a footwear frame, midsole and outsole in FIGS. 1-6 represent portions of the design that form no part of the claim.
